Primary Examiner — Richard Edgar*Assistant Examiner* — Nader Abadir(74) Attorney, Agent, or Firm — Birchwood IP(57) CLAIM

The ornamental design for an oven, as shown and described.

DESCRIPTION

FIG. 1 is a front, left and top perspective view of an oven, showing our new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the oven that form no part of the claimed design.

1 Claim, 8 Drawing Sheets(56)
